ANIMATED CARD DEVICE

Milton D. Youngren, Glencoe, Ill.

Application July 29, 1958, Serial No. 751,739

7 Claims. (Cl. 40—126)

This invention relates to animated devices, particularly those of the type often made of card stock and adapted to be sold as greeting cards or distributed as toys or premiums.

One object of the present invention is to provide a new and improved animated device having a base so that the device will stand alone, and having means whereby the device may be animated by moving a member mounted in the base.

A further object is to provide a new and improved animated device of the foregoing character which may readily be made in three easily formed and easily assembled parts made of card stock.

Another object is to provide a new and improved animated device of the foregoing character which may be distributed flat, but in partially assembled condition, so that it will be a very simple matter for the ultimate user to complete the assembly.

A further object is to provide a new and improved animated device which is so simple and easily assembled that it may be printed as a premium on the back of a cereal box or the like, so that the device may be cut out and assembled by children for use as a toy.

Still another object is to provide a new and improved device of the foregoing character which produces a pleasing animated effect, yet is remarkably simple and low in cost.

Further objects and advantages of the present invention will appear from the following description, taken with the accompanying drawings, in which:

Fig. 1 is a front view of an animated device to be described as an illustrative embodiment of the present invention.

Fig. 2 is a view showing the animated device folded flat, as it may be distributed for use as a greeting card.

Fig. 3 is a top view of the device in its fully assembled condition.

Fig. 4 is a right side elevational view of the device.

Figs. 5, 6 and 7 are views showing the three components of the device, in their initial flat condition.

It is already indicated, the drawings illustrate an animated device 10 which has many applications, but is particularly useful as an animated greeting card, or as an animated device to be given away as a premium. As shown to best advantage in Fig. 4, the device 10 has a base 12 so that the device will stand alone. A front panel 14 extends upwardly from the base 12. Various figures may be printed or otherwise reproduced on the front surface of the upright panel 14. In this case, as shown in Fig. 1, the front panel 14 carries the figure of a clown with a bass drum. It is preferred to mount a movable animating member 16 on the front panel 14. In this instance, the animating member 16 is made in the form of the right arm of the clown shown on the front panel 14. In his right arm the clown is holding a beater for the bass drum. The movement of the member 16 is such as to produce the effect that the

2

clown is beating the bass drum. In this case, the beater is in the somewhat fanciful form of a large toothbrush. Of course, a wide variety of figures may be reproduced on the front panel 14. Moreover, various complementary portions of the figures may be represented by the animating member 16.

In the illustrated device 10 the animating member 16 is adapted to be operated by moving a member 18 along the base 12. In this case, the member 18 is slidably movable on the base 12 and is formed with an upright portion 19 for operating the animating member 16.

It is preferred to form the base 12 and the front panel 14 in a single piece, which may be made of card stock or other sheet material. The illustrated base 12 has top and bottom panels 20 and 22 which are connected together by a fold 24 along the rear edges thereof. The front panel 14 extends upwardly from the bottom panel 12, with a second fold 26 therebetween. It will be seen that the top panel 20 is folded forwardly so as to overlie the bottom panel 22. The slider 18 has a main or central portion 28 which is slidable between the top and bottom panels 20 and 22. The upright operating portion 19 of the slider 18 extends upwardly from the central portion 28, with a fold 30 therebetween.

Means are provided on the base 12 to guide the slider 18. In this case, the bottom panel 22 is formed with two slots 32 and 34 which are substantially at right angles to the folds 24 and 26 and are spaced apart in a direction parallel to the folds. The slider 18 has opposite end portions 36 and 38 which extend through the slots 32 and 34. Thus, the main portion 28 of the slider 18 is above the bottom panel 22, while the end portions 36 and 38 extend beneath the bottom panel. The main portion 28 of the slider is enlarged rearwardly so as to prevent it from passing through the slots 32 and 34. This enlargement produces shoulders 42 and 44 adapted to engage the lower panel 22 at the rear ends of the slots 32 and 34. The shoulders 42 and 44 define the range of movement of the slider 18.

The fold 26 at the front edge of the bottom panel 22 is in line with the front ends of the slots 32 and 34. Thus, the front edge of the slider 18 is immediately behind the front panel 14. The upright operating portion 19 of the slider 18 extends upwardly from the front edge of the slider and thus is also closely spaced behind the front panel 14.

Means are provided to retain the top panel 20 in its normal position over the bottom panel 22. In this case, the righthand front corner of the top panel 20 is formed with a tab 48 adapted to be tucked into the slot 32 immediately above the slider 18.

In order that the front panel 14 may be held in an upright position, it is formed with a brace portion 50 adapted to be folded rearwardly therefrom along a generally vertical fold 52. The brace 50 may be secured to the top panel 20 by means of a tab 54 formed on the lower edge of the brace and adapted to be folded upwardly therefrom along a fold 56. A slot 58 is formed in the top panel 20 to receive the tab 54.

The animating member 16 may be mounted on the front panel 14 in various ways, but in the illustrated construction, the member 16 has a rear portion 60 adapted to extend through a slot 62 in the front panel 14. Tabs 64 are formed on the upper and lower edges of the rear portion 60 to retain the rear portion in the slot 62. The animating member 16 has a front portion 66 which is enlarged so that it will not pass through the slot 62. The fit between the rear portion 60 and the slot 62 is sufficiently loose to permit the animating member 16 to swing freely in the slot. The connection thus afforded between the animating member 16 and the front panel

14 is in the nature of a hinge, so that the front portion 66 of the animating member may swing toward and away from the front face of the front panel. As already indicated, the upright member 19 on the slider 18 is arranged to operate the animating member 16. In this case, the upright member 19 has an upper portion 70 which is formed with a slot 72 adapted to receive the rear portion 60 of the animating member 16. Movement of the slider 18 along the base 12 will thus cause the animating member 16 to swing back and forth.

In the illustrated arrangement, the slots 62 and 72 are substantially vertical, with the result that the animating member 16 swings about a substantially vertical axis. This arrangement might be varied to change the direction of movement of the animating member.

Movement of the slider 18 to the left, as seen in Fig. 1, causes the animating member 16 to be swung against the face of the front panel 14. This makes it appear that the clown, represented on the front panel, is striking the bass drum. When the slider is moved to the right, the animating member 16 is swung away from panel 14.

For use as a premium, the three parts of the animating device may be printed on the back of a cereal box or the like. It is easy for a child to cut out the parts and assemble them to form the complete device, which may be used as a toy. The outlines of the parts and the slots therein may be partially die cut to facilitate the construction of the device. Perforations may be formed along the various fold lines to make the assembly of the device easy.

Of course, the three parts of the device may be supplied already cut out and with the slots formed therein. For compactness, the parts may be supplied flat, but the various fold lines may be scored or perforated so that the device may be assembled very readily.

For use as a greeting card, the device may be supplied completely assembled except for the connection of the brace 50 to the top panel 20 of the base. Leaving this brace 50 unconnected permits the device to be supplied flat so that the brace may be inserted in an envelope and mailed as a greeting card. With the brace 50 disconnected, the front panel may be folded down into the plane of the bottom panel 22, as shown in Fig. 2. The brace 50 is likewise folded into the plane of the bottom panel. The top panel 20 may be left with the tab 48 in the slot 32, so as to hold the top panel against the bottom panel 22. Alternatively, the top panel 20 may be detached from the slot 32 and swung into the plane of the bottom panel 22, as shown in Fig. 2.

The animating device may be employed as an advertising medium, in which case various advertising messages may be formed on the front panel 14, the bottom panel 22, the top of the top panel 20 and the exposed portions of the slider 18.

It will be apparent that the device produces a pleasing animation which will often be amusing, particularly to children. Moreover, the assembly of the device is so easy that it may readily be done by a child. The device is so low in cost that it may be distributed freely as a premium or advertising medium.

Various modifications, alternative constructions and equivalents may be employed without departing from the true spirit and scope of the invention, as explained in the foregoing description and defined in the following claims.

I claim:

1. An animated card, comprising a one-piece member made of sheet material, said member having a bottom panel, a top panel, with a first fold connecting said top panel to said bottom panel at the rear edges of said panels, and an upright panel extending upwardly substantially at right angles to said bottom panel with a second fold connecting the lower edge of said upright panel to the front edge of said bottom panel, said bottom

panel having first and second substantially parallel slots therein extending in a direction substantially at right angles to said first and second folds, said folds being substantially parallel to each other, said slots being spaced apart in a direction substantially parallel to said folds, a slider made of sheet material and having a central portion slidable between said top and bottom panels, said slider having end portions extending downwardly through said first and second slots, said top panel having a tap thereon disengageably receivable in one of said slots for retaining said top panel in substantially parallel relation to said bottom panel, said slider having an upright member extending generally at right angles from said central portion with a fold connecting the lower edge of said upright member to the front edge of said slider, said upright member extending between the front edge of said top panel and said upright panel, said upright member being movable behind said front panel in closely spaced relation thereto, said front panel having a brace portion folded rearwardly therefrom, with a second tab on the lower edge of said brace portion, said top panel having a slot therein for disengageably receiving said second tab to hold said upright panel in an upright position, an animating member having a front portion in front of said upright panel and a rear portion behind said upright panel, said upright panel having a slot therein for disengageably receiving said rear portion, tab means on said rear portion for retaining said rear portion in said last-mentioned slot for swinging movement, said upright panel and said animating member having relatively movable complementary portions of a figure thereon, and a slot in said upright member of said slider for disengageably receiving said rear portion of said animating member for swinging said animating member in response to movement of said slider through said first and second slots.

2. An animated device, comprising a main member made of sheet material and having a bottom panel, a top panel overlying said bottom panel and a front panel extending upwardly from the front edge of said bottom panel, said member having a first fold between the rear edges of said top and bottom panels, and a second fold between the bottom edge of said front panel and the front edge of said bottom panel, said front panel having a brace portion folded rearwardly therefrom, with a tab on said brace portion, said top panel having a slot therein for receiving said tab, said bottom panel having first and second generally parallel slots therein extending generally at right angles to said second fold and spaced apart along a direction generally parallel to said second fold, a slider made of sheet material and having a central portion slidable between said top and bottom panels, said slider having end portions extending through said slots, said slider having an upright member extending upwardly from said central portion, with a front therebetween, said upright member extending between the front edge of said top panel and the rear side of said front panel, a member mounted on said front panel for animating movement, and means on said upright member for moving said animating member in response to sliding movement of said slider through said slots.

3. An animated device, comprising a bottom panel, a top panel overlying said bottom panel, means connecting the rear portion of said top panel to the rear portion of said bottom panel, a front panel connected to said bottom panel and extending upwardly from the front edge thereof, a slider made of sheet material and slidably between said top and bottom panels, said slider having an upright member extending upwardly therefrom and slidably between the front edge of said top panel and the rear side of said front panel for animating movement with respect to said front panel in response to sliding movement of said slider between said top and bottom panels.

4. An animated display device, comprising a base

member made of sheet material and having adjacent upper and lower interconnected panels, an upright display panel made of sheet material and mounted on said base, one of said panels of said base having a pair of longitudinally spaced transversely extending slots therein, a slider made of sheet material and having opposite end portions extending through said slots to mount said slider on said base for sliding movement between said upper and lower panels, and an upright portion folded upwardly from said slider and extending upwardly between said upright panel and the front of said top panel for animating movement adjacent said upright display panel.

5. An animated device, comprising a main member made of sheet material and having a bottom panel, a top panel overlying said bottom panel and a front panel extending upwardly from the front edge of said bottom panel, said member having a first fold between the rear edges of said top and bottom panels, and a second fold between the bottom edge of said front panel and the front edge of said bottom panel, said bottom panel having first and second generally parallel slots therein extending generally at right angles to said second fold and spaced apart along a direction generally parallel to said second fold, a slider made of sheet material and having a central portion slideable between said top and bottom panels, said slider having end portions extending through said slots, said slider having an upright member extending upwardly from said central portion, with a fold therebetween, said upright member extending between the front edge of said top panel and the rear side of said front panel, a member mounted on said front panel for animating movement, and means on said upright member for moving said animating member in response to sliding movement of said slider through said slots.

6. An animated card, comprising a one-piece member made of sheet material, said member having a bottom panel, a top panel, with a first fold connecting said top panel to said bottom panel at the rear edges of said panels, and an upright panel extending upwardly substantially at right angles to said bottom panel with a second fold connecting the lower edge of said upright panel to the front edge of said bottom panel, said bot-

tom panel having first and second substantially parallel slots therein extending in a direction substantially at right angles to said first and second folds, said folds being substantially parallel to each other, said slots being spaced apart in a direction substantially parallel to said folds, a slider made of sheet material and having a central portion slideable between said top and bottom panels, said slider having end portions extending downwardly through said first and second slots, said top panel having a tab thereon disengageably receivable in one of said slots for retaining said top panel in substantially parallel relation to said bottom panel, said slider having an upright member extending generally at right angles from said central portion with a fold connecting the lower edge of said upright member to the front edge of said slider, said upright member extending between the front edge of said top panel and said upright panel, said upright member being movable behind said front panel in closely spaced relation thereto, and an animating member movably mounted on said front panel and connected to said upright member for animating movement in response to movement of said slider.

7. An animated device, comprising a bottom panel, a top panel overlying said bottom panel, means connecting the rear portion of said top panel to the rear portion of said bottom panel, a front panel connected to said bottom panel and extending upwardly from the front edge thereof, said panels being made of sheet material, a slider made of sheet material and slideable between said top and bottom panels, said slider having an upright member extending upwardly therefrom and slideable between the front edge of said top panel and the rear side of said front panel and means mounted on said front panel and connected to said upright member for animating movement with respect to said front panel in response to sliding movement of said slider between said top and bottom panels.
